Primary Examiner — Darlington Ly

CLAIM

The ornamental design for a mud flap kit, as shown and described.

DESCRIPTION

FIG. 1 is a front side perspective view of a mud flap kit, showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a back side perspective view thereof.

The broken lines in the drawings depict portions of the mud flap kit that form no part of the claimed design.
